(57) **CLAIM**

The ornamental design for a hair dryer as shown and described.

DESCRIPTION

FIG. 1 is a perspective view of a hair dryer showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a left perspective view thereof;

FIG. 9 is an enlarged detail view of area 9 shown in FIG. 1; and,

FIG. 10 is an enlarged detail view of area 10 shown in FIG. 3.

The long dashed broken lines in FIGS. 1, 3, 9 and 10 depict the boundaries of the enlarged views and form no part of the claimed design. The additional broken lines in the drawings depict portions of the hair dryer that form no part of the claimed design.
